DESIGN FOR A TWINE REEL

Carroll B. Colby, Briarcliff Manor, N. Y.

Application January 18, 1934, Serial No. 50,445

Term of patent 3½ years

To all whom it may concern:

Be it known that I, CARROLL B. COLBY, a citizen of the United States, residing at Horsechestnut Road, Briarcliff Manor, in the county of Westchester and State of New York, have invented a new, original, and ornamental Design for a Twine Reel, of which the following is a specification, reference being had to the accompanying drawing, forming part thereof.

Fig. 1 is a plan view, and Fig. 2 is a side elevation of a twine reel showing my new design.

I claim:

The ornamental design for a twine reel as shown.

CARROLL B. COLBY.
